(57) **CLAIM**

The ornamental design for a mailbox, as shown and described.

DESCRIPTION

FIG. 1 is a top, front, and right side perspective view of a mailbox showing our new design;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a bottom, front and left side perspective view thereof;

FIG. 9 is a top, front, and right side perspective view thereof, with the signal shown in a raised position; and,

FIG. 10 is a top, front and left side perspective view thereof, showing the details of the roof.

Our mailbox is characterized by two accessible doors, a fence surrounds the mailbox's periphery and a double roof special design.
